R. W. BURNETT,
MEANS FOR REINFORCING CAR ENDS.
APPLICATION FILED FEB. 9, 1918.

1,287,631.

Patented Dec. 17, 1918.

Inventor
Richard W. Burnett

George J. Haight
Atty.

UNITED STATES PATENT OFFICE.

RICHARD W. BURNETT, OF ALBANY, NEW YORK.

MEANS FOR REINFORCING CAR ENDS.

1,287,631.

Specification of Letters Patent. Patented Dec. 17, 1918.

Application filed February 9, 1918. Serial No. 216,178.

To all whom it may concern:

Be it known that I, RICHARD W. BURNETT, a citizen of the United States, residing at Albany, in the county of Albany and State 5 of New York, have invented a certain new and useful Improvement in Means for Reinforcing Car Ends, of which the following is a full, clear, concise, and exact description, reference being had to the accompanying 10 drawings, forming a part of this specification.

My invention relates to means for reinforcing car ends.

One of the objects of my invention is to 15 provide a certain efficient and durable means for tying together the end posts of the car frame and reinforcing means employed upon the car's end.

Another object is to provide a member 20 adapted to receive the lower ends of a car's end posts and at the same time to tie them to the end sill and to reinforcing members upon the end of the car.

Other objects will appear from the 25 description of my invention hereinafter given.

It is well understood in the railroad art that the ends of cars must be exceedingly strong in order that they may resist the shocks occasioned by the shifting of cargo, 30 and to this end it is important that the portions of the car overhanging the bolster at either end shall be securely bound together in order to strengthen the car end, and also in order to transmit, as far as practicable, 35 to the whole body of the car, the impacts delivered through the draft rigging to the center sills to which the draft rigging is usually directly applied. In constructions heretofore, it has not been unusual to place the 40 lower ends of the car posts, as for instance in a box car structure, in a socket back of the end sill, particularly where metal end sills are employed. It has been a common practice to support these sockets by wooden members, which through decay, wear and loosening 45 tend to ultimately relieve the end posts from support and to permit the driving out of the ends under impacts of service or impacts of the cargo.

50 In the invention hereinafter more specifically described, I provide members which furnish sockets for the lower ends of the end posts, each of said members being held in position not only by connection to the end 55 sill through some intermediate member, but

in preferable construction through direct connection with the end sill, furnishing a durable and rigid socket member, and also through connection to reinforcing means, preferably on the outer face of the end of 60 the car. The end sill, end post and the said reinforcing means are all tied together in an integral structure so that the whole end of the car overhanging the bolster is tied together, one part assisting in supporting the 65 other, and all giving a rigid construction adapted to successfully meet the service shocks delivered through the draft rigging to support the whole end structure of the car, and to prevent the breaking out of the 70 car end through the shifting of the cargo.

In the drawings forming a part of this specification, Figure 1 is an end view of a portion of a car end embodying my invention; Fig. 2 is a cross section taken on line 75 2-2 of Fig. 1; Fig. 3 is a vertical section taken on line 3-3 of Fig. 1; and Fig. 4 is a detail view of an embodiment of the connecting member adapted to tie a car end reinforcing member, the end sill and the end 80 posts together.

Referring to the drawings, the numeral 5 indicates a portion of an end of a car. The upper portions of center sills are indicated by the dotted lines at the numerals 6 in Fig. 1. The end sheathing of the car is indicated at the numeral 7. The car end reinforcing means, as for instance, vertically arranged Z-bars, are indicated by the numerals 8. The lower ends of the end posts are shown at 9 90 in the dotted lines in Fig. 1 of the drawing, and are indicated by the same numerals in Figs. 2 and 3. The connecting member 10 is provided with a socket 11 in which the lower end of an end post is received. The said 95 member is preferably a casting, and the socket for the end post is open at one end, as indicated at 12, is closed at either side by the upstanding flanges 13 and 14, and at the other end by the flange 15. The flange 15 is adapted to engage the reinforcing member 8, and in the particular form of reinforcing member shown, a Z-bar is secured by the rivets 16 to the web 17 thereof. The flange 14 is provided with an outstanding lip 18 which 100 passes over the end sill 19, which in the particular form shown in the drawings is channel shape, with the lip 18 resting upon the upper flange 20 thereof. The flange 14 has a downwardly extending portion 21 110

which passes along the inner face of the end sill 19, and in the specific embodiment of my invention shown in the drawings is offset as at 22 to pass over the member 23, through which it is secured to the end sill by suitable means, as for instance, the rivets 24. The lip 18 is provided with an upstanding lug 25, suitably braced, as for instance, by the triangular members 26, and is secured 10 to the inner flange of the Z-bar reinforcing member by suitable means, as for instance, the rivet 27.

All the parts of the connecting member 10 are preferably integrally formed, and it will 15 be understood that the shape thereof may be suitably altered to fit different forms of end sill and reinforcing car end members and end posts than those shown in the drawings without departing from the spirit of my invention.

In many railroad cars employing reinforcing end members such as the Z-bars shown, it is not practical to extend the lower ends of the same below the upper face of 25 the end sill. In such constructions, my invention is particularly desirable, and also it is of great value in this: that in repairing car ends, the connecting member can be readily introduced without disassembling 30 great portions of the car end structure, as the open end 12 and the conformation of the connecting member 10 permits the slipping in of said member under an end post and positioning it for ready attachment to the end 35 sill and the outside reinforcing members employed upon the car end.

While it is perfectly feasible to close the end 12 with a flange forming a four-sided socket for the lower end of the end post, for 40 the reasons just given I prefer the open end 12.

The member 23 is sometimes employed to support the nailing strip 28, but when the member 23 is not employed the member 10 45 may be made without the offset 22 in the depending flange 21.

It will be noted that through the invention described, in addition to some of the advantages already pointed out, the center sills 50 of the car which are secured to the end sills are supported by the whole end frame of the car, so that the entire structure is employed to prevent downward bending of the center sills frequently occasioned by the eccentric 55 delivery of the blows of the draft gear to the car underframe. Also, it will be observed that the bringing of the member 10 inside of the end sill and employing the depending flange 21 relieves the connecting 60 member therefor of tensile strain.

In repair work, not only the difficulty and disarrangement of the car end is avoided in reinforcing ends, but great expense is saved in obviating the necessity of spreading the 65 car vertically and lifting the end posts in

order to place sockets underneath them. All of this difficulty and expense my invention avoids.

The member 10, in addition to the foregoing, may be broadly said to perform a triple function; that is, it provides a supporting socket for an end post, a tying member for the reinforcing member of the car end, and a connection for both of these members to the end sill of the car.

I claim:

1. In a car, in combination with an end post, an end sill, and reinforcing means for a car end, of a connecting member having a seat to accommodate the end post and means 80 for connecting the same to the reinforcing member and the end sill.

2. In a car, an end post, a reinforcing member and an end sill, in combination with a connecting member therefor, said connecting member having a socket to receive the lower end of the end post, a flange secured to the reinforcing member, and means for attaching it to the end sill.

3. In a car, the combination with an end 90 post, a reinforcing member for the car end, and an end sill, of a connecting member having a seat to accommodate the end post, a flange connecting said member to the reinforcing member, and means for securing the 95 connecting member to the end sill, the said seat being open on one side whereby the same may be placed by lateral movement under the end post.

4. In a car, the combination with an end 100 post, a reinforcing member for the car end, and an end sill, of a connecting member therefor, the said member being provided with a laterally open socket to receive the end post, and flanges secured to the reinforcing member and the end sill.

5. In a car, the combination with an end post, a reinforcing Z-shape member for the car end, and an end sill, of a connecting member having a socket to receive the end 110 post, a flange secured to the end sill, a flange secured to a web of the Z-shaped member, and a flange secured to one of the flanges of the Z-shaped member.

6. In a car, the combination with an end 115 post, a reinforcing member for the car end, and an end sill, of a connecting member having a laterally opening socket to receive the end post, a flange secured to the reinforcing member, a laterally extending flange 120 passing over the end sill, and a depending flange secured to the end sill.

7. In a reinforced wood car construction, the combination with the end wall having a wood post, a reinforcing metal beam secured to the outer face of the wall and paralleling said post, and an end sill, said reinforcing beam terminating adjacent the top of said end sill; of a connecting plate extending from the inside to the outside of the 130

end wall and located beneath the bottom of both said post and said beam, said plate being secured to the end sill and engaged with the post and beam to thereby prevent 5 the latter from shifting lengthwise of the car and relative to said end sill.

8. As an article of manufacture, a member for connecting an end post in a car, a reinforcing member for the car end, and an 10 end sill, the said member comprising a casting having a laterally opening socket to receive an end post, a flange for attachment to the reinforcing member, a horizontal flange to engage the upper face of an end sill, and 15 a depending flange at right angles thereto.

9. In car construction, the combination with a car end wall having a wood post sheathing, outer reinforcing beam paralleling said post, and an end sill; of a post retaining casting having a horizontal web adapted to be positioned under the bottom of said end wall wood post, an integral shouldered portion adapted to be secured to said beam, and an integral shouldered portion 20 adapted to engage the end sill to prevent said casting being forced lengthwise 25 of the car outwardly beyond the end sill.

10. As an article of manufacture, a post securing casting for reinforcing wood car 20 end walls, said casting having a horizontal web adapted to be extended under an end

post, an upwardly vertically extending flange adapted to be secured to a reinforcing member of the car wall on the outer side of the sheathing, and an integral downwardly extending flange adapted to engage the rear face of the car end sill to prevent the casting from sliding outwardly endwise of the car when the casting is in place. 35

11. As an article of manufacture, a casting 40 adapted for use on reinforced wood car end walls, said casting having a horizontal web portion adapted to be inserted under the end wall of the car, an outer upwardly and vertically extending flange adapted to 45 be secured to a reinforcing member on the outer side of the sheathing of the car wall, and an integral downwardly extending shouldered portion at its inner end adapted to engage a coöperating shoulder on the 50 car end sill to thereby prevent the casting and said reinforcing member from being forced outwardly endwise of the car when the casting is in place.

In witness that I claim the foregoing I 55 have hereunto subscribed my name this 24th day of Jan., 1918.

RICHARD W. BURNETT.
